DESIGN FOR A TEXTILE FABRIC

Albert Y. Toriumi, Honolulu, Territory of Hawaii, assignor to Japan Merchandise Company of Honolulu, Honolulu, Territory of Hawaii

Application July 9, 1938, Serial No. 78,379

Term of patent 7 years

To all whom it may concern:

Be it known, that I, Albert Y. Toriumi, a citizen of the United States of America, residing at Hono-olulu, in the county of Honolulu and Territory of Hawaii, have invented a new, original, and ornamental Design for Textile Fabrics, of which the following is a specification, reference being had to the accompanying drawing, forming a part thereof; wherein the figure is a face view of a textile fabric showing my new design.

I claim:

The ornamental design for a textile fabric, substantially as shown.

ALBERT Y. TORIUMI.
